(57) **CLAIM**

The ornamental design for a textile cover for a drinking vessel, as shown and described.

DESCRIPTION

FIG. 1 is a perspective view of a textile cover for a drinking vessel showing my new design;

FIG. 2 is a front elevational view;

FIG. 3 is a rear elevational view;

FIG. 4 is a left side elevational view;

FIG. 5 is a right side elevational view;

FIG. 6 is a top plan view;

FIG. 7 is a bottom plan view;

FIG. 8 is a perspective view showing the device in actual use on a drinking vessel; and,

FIG. 9 is similar to FIG. 1, but of a modified design wherein the device is similar to that shown in FIGS. 1-8, but having a modified end flap.

The broken lines are for illustrative purposes only and form no part of the claimed design.
